UNITED STATES PATENT OFFICE.

SEWALL K. OLIVER, OF COLUMBIA, SOUTH CAROLINA.

WARP TAKE-UP AND TENSIONING MECHANISM FOR LOOMS.

1,423,729.

Specification of Letters Patent. Patented July 25, 1922.

Application filed March 14, 1921. Serial No. 451,977.

To all whom it may concern:

Be it known that I, SEWALL K. OLIVER, a citizen of the United States, residing at Columbia, in the county of Richland and State of South Carolina, have invented certain new and useful Improvements in Warp Take-Up and Tensioning Mechanism for Looms; and I do hereby declare the following to be a full, clear, and exact description of the same, reference being had to the accompanying drawings, forming part of this specification.

This invention relates to looms and more particularly to an improved take-up mechanism that will maintain the warp threads under proper tension after the threads have been drawn back and slacked to permit what is called a "pick-out."

In the operation of weaving it frequently occurs that a weft thread breaks or a defective yarn becomes woven in on the warp threads so as to make a defect in the finished cloth and it is necessary, in certain grades of goods to draw out these defective threads and then, after pulling the warp threads back a few inches and properly tensioning them, start up the weaving again so as to replace the defective threads with new weft threads—in other words, reweave the portion of the cloth that was defective. This operation is known as making a "pick-out."

Where the warp yarns are fed from a beam, a pick-out can be accomplished by winding back the beam or spool from which the yarns unwind but in other methods of weaving, such for instance, as where the warp yarns are fed from a large number of spools in a rack or creel, great difficulty has been experienced in effecting a pick-out. In this last method of weaving the warp yarns, coming from the spools in the creel, are passed through a guide bar having a series of holes in it for maintaining the threads in proper position. Occasionally the warp threads are placed under tension by frictional means within the creel but usually said threads, after having been passed through the guide bar, are then passed around a friction drum before going into that portion of the loom where the weaving takes place, the friction drum properly tensioning the threads and controlling the speed with which they are fed to the loom, all as is well understood in the art. This method

of weaving from a creel possesses some important advantages, particularly as applied to some special classes of goods, but, with other classes of goods, such as that used in weaving canvas, it is impossible to pull the warp threads back evenly and satisfactorily so that a pick-out can be made, due to the warp threads slipping when the friction drum is turned backwards, and creel looms, have practically been abandoned for the weaving of goods where it is necessary to make pick-outs.

One object of the present invention, therefore, is to provide auxiliary tensioning means by which slack warp threads between the let-off devices of the loom and the point where the goods are actually woven may be taken up and held under proper tension between those points without affecting those portions of the warp threads extending from the friction drum back to the creel or other source of warp supply.

A further object of the invention is the provision of means that will maintain the proper tension on the warp threads between the friction drum and shed forming mechanism until the reweaving necessitated by the pick out has been accomplished.

In the accompanying drawings,—

Figure 1 is a side elevation of a loom embodying the present improvements, the loom being shown, more or less, in a conventional manner.

Fig. 2 is a detail view of the warp thread engaging devices for taking up and tensioning the threads; and

Fig. 3 is a detail front elevation of the operating mechanism for the take up and tensioning members.

One of the side main frame members of the loom is indicated by the reference numeral 10 and the friction drum 11 extends transversely of the loom. As is usual, the friction drum 11 is rotatably mounted in the frame, its speed of rotation being controlled by a brake band 12 acting upon a small drum 12^a geared to drum 11. The warp yarns 13 are supplied from any suitable source (not shown) and are partially wound around the friction drum 11 from which they pass to the heddles 14 of the shed forming mechanism. At this point the weft thread is run in on the warp threads, and each weft thread beaten up by the lay sword

15, after which the woven cloth 18 is taken up by the take up rolls 16, 17. The operating connections for the take up rolls are of the type found in the well known Crompton-Knowles loom and consist essentially of a cross shaft 19 journaled centrally of the main frame 10 and provided with a gear wheel 20 adapted to rotate a cam wheel 21. Cam wheel 21, through a link 22, imparts 10 a rocking motion to a loosely mounted lever 23 having a ratchet or pawl 24 on its upper end adapted to impart an intermittent rotary motion to a ratchet wheel 25 mounted on a shaft 26 and shaft 26 rotates the take-up rolls 16, 17 by a series of gear wheels, 15 27, 28, 29 and 30, the last mentioned gear meshing with a gear on take-up roll 16 and the two rolls being geared together. The construction and operation of the parts described is, of course, well understood in the art, and further description is unnecessary.

Should a defective weft thread be woven in on the warp threads, the ratchet 24 and a safety ratchet 31 are disengaged from 25 ratchet wheel 25 and the take up rolls are rotated backward. The defective weft threads are then removed and the warp yarns pulled back, causing them to become slack between the heddles 14 and friction drum 11. It is necessary, however, that said warp threads be placed under tension before weaving is again commenced and this has generally been accomplished heretofore by rotating the friction drum backwardly, 35 the warp yarns being placed under tension between the drum and source of supply, the slack at this last point being taken up by some suitable mechanism or by returning it to the source of supply, although this last 40 method is not practical in looms fed from creels, due to the large number of spools. In actual practice, however, removal of the slack beyond the friction drum by reversing the rotation of the latter has proved unsatisfactory and unsuccessful, particularly 45 with hard, firm goods such as used in the manufacture of canvas, as materials having these characteristics almost invariably slip when the movement of the friction drum is attempted to be reversed, resulting in a 50 number of single threads becoming slack between the drum and heddles even though means are provided for taking up the slack between the drum and creel or other source 55 of supply.

The present invention, therefore, contemplates the provision of a mechanism that will take up or tension the slack warp threads intermediate the friction drum or 60 other let off device and shed forming mechanism without the friction drum or that portion of the threads between the friction drum and creel being moved or otherwise affected. The preferred form of 65 mechanism for accomplishing this result is

illustrated in the accompanying drawings, it being understood that the present invention is not limited to the particular structure shown except where the claims specify such structural limitations.

In this preferred construction, a pair of cross bars 32, 33, or other suitable means that will engage all the warp threads, are arranged transversely of the frame intermediate the friction drum 11 and heddles 14 and the warp yarns pass through between these two bars. One of said bars, is fixed and the other bar, is movably mounted, suitable mechanism being provided for raising and lowering said movable bar. Normally the two bars are positioned practically in the same horizontal plane adjacent the upper surface of friction drum 11, serving practically as guides for the warp threads but when said threads are slackened or backed up for the purposes of making a pick-out, the movable bar is moved relatively to the fixed bar to a position (as indicated in dotted lines in Fig. 1) where the increased distance traveled by the threads between the drum and heddles places said threads under the proper tension to permit weaving to be resumed. After the weaving operation has been resumed the movable bar is automatically returned to its normal position by 80 connections actuated by a driven part of the loom and hereinafter described.

Preferably the bar 32 is fixedly mounted in the side frame members 10 of the loom and bar 33 is carried on two upwardly extending rotatable screw-threaded posts 34 mounted on the loom frame, said cross bar 33 being provided with screw-threaded sleeves 35, at its ends, engaging the screw threads of the posts whereby rotation of the posts will elevate or depress said cross bar. Mounted on the lower ends of the posts 34 are bevel gears 36 geared to similar gears 37 on a transverse shaft 38 mounted in the main frame immediately below the lower ends of posts 34. Shaft 38 is provided at one end with a bevel gear 39 cooperating with a pinion 40 on one end of a shaft 41 extending to the front of the loom, at which point it is provided with suitable means, such as a hand wheel 42, for manually rotating the shaft.

Rotation of hand wheel 42 and shaft 41 in a clockwise direction will, through the pinion and gears, rotate screw posts 34 and elevate bar 33, said bar being raised to a position where the warp threads will be backed up and placed under proper tension. Manual operation of the mechanism for placing the warp threads under tension or drawing them back to restore the relation of the lay and perfect part of the weave is very advantageous in that the amount of tension under which the threads are put is under complete control of the operator, although 130

it is practically impossible to injure the threads by placing them under too great a tension because after the slack in them has been taken up, additional pressure on bar 5 33 will merely draw more warp from the source of supply.

The warp threads having been properly tensioned, weaving is resumed and, in order that movable bar 33 may be returned to its 10 normal position where it can again be utilized for drawing back and tensioning the threads when a pick out is made, suitable mechanism is provided for rotating shaft 41 in a reverse direction at a fixed, predetermined speed whereby the downward movement of the bar will be regulated relatively to the feeding of the warp threads to the loom and said threads maintained under the proper weaving tension by the bar until said 15 bar has reached its normal position. After that the normally operative tensioning devices are alone effective to regulate the threads. This lowering mechanism preferably comprises a ratchet wheel 43 mounted 20 on shaft 41 and adapted to be engaged by a pawl 44 journaled in a pair of arms 45 in the form of bell crank levers pivotally mounted on said shaft. Arms 45 are connected by links 46 to one arm 47 of a bell 25 crank lever whose other arms 48 is provided with an aperture through which extends an operating bar 49 pivotally connected to the lower end of the lay sword 15. Stops, in the form of collars 51, are secured 30 on said bar, one on each side of operating bar 49, and a coil spring 52 surrounds said bar, being interposed between the outer stop 35 and arm 48 of the bell crank lever.

When the cross bar 33 is in an elevated 40 position, the power of spring 52 is such that each time the lay sword 15 is retracted after having beat up a woven weft thread, the bell crank lever will be rocked, arm 48 of said lever being depressed, and this downward 45 movement of said arm will, through links 46 and arms 45, actuate the ratchet 44 and ratchet wheel 43. This imparts a reverse rotary motion to shaft 41, and, as will be apparent, the cross bar 33 will gradually be 50 lowered. The downward movement of bar 33 is limited by stops 53 on posts 34 and after the bar reaches the limit of its downward movement the rocking motion of the lay sword will be taken up by spring 52, no 55 movement being imparted to the connections that actuate the ratchet 44. When the cross bar 33 is to be elevated by the hand wheel 42 it is only necessary to throw the pivoted pawl or ratchet 44 out of engagement with the ratchet wheel and after the slack in the threads has been taken up said pawl is thrown back to its former position. 60

The connections for lowering the bar 33 need not necessarily be actuated by the lay 65 sword but they may be connected to any

suitable moving part of the loom that will serve to lower the bar at a speed such as will maintain the threads under the proper weaving tension until said bar has been returned to its normal position where the 70 usual tensioning means of the loom alone become effective. While various forms of mechanisms for elevating and depressing said bar readily suggest themselves, the present invention consists primarily in 75 means for taking up the slack in the warp threads between the friction drum and heddles without affecting those portions of said threads on the opposite side of the friction drum and the following claims are to be limited only to the structural details expressly included therein.

In the preferred arrangement the bar 33 is lowered at a speed which alone would not give the desired feed of warp threads and 80 hence the friction drum is always in operation but its movement is reduced during the time bar 33 is letting off the threads to supply a part of the required feed.

What is claimed is:

1. In a slack take-up device for looms, the combination with the warp delivering and shed forming mechanisms, of means for taking up and tensioning the slack warp threads intermediate the warp delivering and shed 90 forming mechanisms, said take up and tensioning means being supported independently of the warp threads and being normally inoperative, and means for manually operating said take up and tensioning means independently of the warp delivering mechanism.

2. In a slack take up device for looms, the combination with the warp delivering and shed forming mechanisms, of normally 105 inoperative means for taking up and tensioning the slack warp threads intermediate the warp delivering and shed forming mechanisms, and connections for positively actuating said take up and tensioning means, 110 said actuating connections being manually operable and independent of the warp delivering mechanism, whereby the slack warp threads may be placed under a tension independently of the warp delivering mechanism.

3. In a slack take up device for looms, the combination of the let off and shed forming mechanisms, slack take up means adapted to vary the length of the path between the let off and shed forming mechanisms traveled by the warp threads, and manually operable connections for actuating said slack take up means to increase the path traveled by said threads, and means for automatically decreasing said path.

4. In a take up device for looms, the combination with the friction drum and heddles, of normally inoperative warp take up and tensioning and let off means, and means for rendering said means operative, said warp 130

- take up and tensioning and let off means engaging the warp threads intermediate the drum and heddles.
5. In a take up device for looms, the combination with warp delivering and shed forming devices, of normally inoperative warp take up, tensioning and let off means located between the warp delivering and shed forming devices, mechanism for rendering said take up and tensioning and let off means operative, whereby slack in the warp threads may be taken up intermediate the warp delivering and shed forming devices, and connections for automatically returning said take up, tensioning and let off means to its inoperative position.
6. In a take up device for looms, the combination with the warp delivering and shed forming devices, of warp take up and tensioning and let off means movable into and out of operative position intermediate the warp delivering and shed forming devices, manually operable means for moving said take up and let off means into operative position, and automatically operable means for returning said take up and let off means to inoperative position.
7. In a take up device for looms, the combination with the warp delivering and shed forming devices, of warp take up and tensioning and let off means movable into and out of operative position, connections for moving said means into operative position and connections for returning said means to their inoperative position at a predetermined rate of speed.
8. In a take up device for looms, the combination with warp delivering and shed forming mechanisms, of warp take up and tensioning and let off means comprising a pair of bars between which the warp threads pass intermediate the delivering and shed forming mechanisms, means for moving one of said bars relatively to the other whereby slack in the warp threads is taken up and said threads held under tension, and means for returning the movable bar to its normal position.
9. In a take up device for looms, the combination with the warp delivering and shed forming devices, of warp take up and tensioning and let off means comprising an upwardly movable bar over which the warp threads pass, means for moving said bar upwardly whereby slack in the warp threads is taken up and said threads held under tension, and means operated at a predetermined rate of speed for returning said bar to its normal position.
10. In a take up device for looms, the combination with the warp delivering and shed forming mechanisms, of warp take up and tensioning and let off means comprising a pair of bars between which the warp threads pass, said bars being located intermediate the warp delivering and shed forming mechanisms, means for moving one of said bars relatively to the other to increase the path of travel of the threads from the delivering to the shed forming devices, whereby slack warp threads intermediate said devices are held under tension, and means for returning said bars to their normal relative positions.
11. In a take up device for looms, the combination with the warp delivering and shed forming devices, of warp take up and tensioning and let off means comprising a pair of bars between which the warp threads pass, said bars being located intermediate the warp delivering and shed forming devices, manually operable means for moving one of said bars relatively to the other, and means operable at a predetermined rate of speed for returning the bars to their normal relative positions.
12. In a warp take up and tensioning and let off device for looms, the combination of warp delivering and shed forming devices, a pair of upwardly extending posts, a movable bar carried by said posts and adapted to engage the warp threads intermediate the warp delivering and shed forming devices, and means for elevating and lowering said bar on said posts.
13. In a warp take up and tensioning and let off device for looms, the combination of a pair of upwardly extending rotatable screw-threaded posts, a cross bar carried on the posts, adapted to engage the warp threads intermediate the warp delivering and shed forming mechanisms of the loom, and means for rotating said posts for elevating and lowering the cross bar.
14. In a warp take up and tensioning and let off device for looms, the combination of a pair of upwardly extending posts, a movable cross bar carried by the posts, adapted to engage the warp threads intermediate the warp delivering and shed forming mechanisms of the loom, manually operable means for elevating said cross bar, and automatically operable means for lowering the cross bar, said lowering means being actuated at a predetermined rate of speed.
15. In a take up device for looms, the combination of a pair of upwardly extending rotatable screw-threaded posts, a cross bar carried on said posts, adapted to engage the warp threads intermediate the warp delivering and shed forming devices of the loom, gears on the lower ends of said posts, a shaft, manually operable means for rotating said shaft in one direction, a ratchet wheel on said shaft and a pawl for rotating the shaft in the opposite direction, a pinion on said shaft, a second shaft, and gears on said second shaft engaging said pinion and the gears on the upwardly extending posts.
16. In a take up device for looms, the com-

bination of a pair of upwardly extending rotatable screw-threaded posts, a cross bar carried by the posts, adapted to engage the warp threads intermediate the warp delivering and shed forming devices of the loom, gears on the lower ends of the posts, a shaft, manually operable means for rotating said shaft in one direction, a ratchet wheel mounted on the shaft, a pawl movable into and out

of engagement with said ratchet wheel, connections intermediate the pawl and a moving part of the loom for rotating said shaft in the opposite direction, a pinion on the shaft, a second shaft, and gears on said second shaft engaging said pinion and the gears on the rotatable posts. 10 15
